CLAIM

The ornamental design for an optical communication connector, as shown and described.

DESCRIPTION

FIG. 1 is a perspective view of the front, bottom and left side of an optical communication connector showing our new design.

FIG. 2 is a front view thereof.

FIG. 3 is a top plan view thereof.

FIG. 4 is a bottom view thereof.

FIG. 5 is a left side view thereof.

FIG. 6 is a right side view thereof; and,

FIG. 7 is a perspective view thereof in the separated condition.

The rear view is a mirror image of the front view.
